UNITED STATES PATENT OFFICE.

MATTHEW F. BRAMLEY, OF CLEVELAND, OHIO.

RAILWAY PAVEMENT AND METHOD OF MAKING IT.

Application filed July 18, 1924. Serial No. 726,758.

To all whom it may concern:

Be it known that I, MATTHEW F. BRAMLEY, a citizen of the United States, residing at 11420 Harbor View Drive, city of Cleveland, in the State of Ohio and county of Cuyahoga, have invented a new and useful Improvement in Railway Pavements and Methods of Making Them, of which the following is a specification, the principle of 5 the invention being herein explained and the best mode in which I have contemplated applying that principle, so as to distinguish it from other inventions.

My invention pertains to a railway construction and more particularly to a railway pavement or that portion of a pavement which is located between the rails of one particular track. The method of building my invention is likewise believed to be novel. 10 Heretofore, so far as I am aware, street pavements between track rails have generally been what may be termed a unitary structure, either of cemented brick, tarred or cemented cobble stones or an asphaltum 15 layer. While said pavement strips have been mainly at an approximate level with the treads of the rails, a recess or depression had to be provided alongside of the inner side of the rails of sufficient depth to permit the 20 rotating passage of the wheel flange and of sufficient width to allow for the inevitable side play of the wheel flange. The outer borders of the brick or cobble stone pavements could not be feasibly spaced an 25 adequate distance from the rails because lateral support for the imbedded border units even though a yielding filler like tar be supplied. In consequence, the wheel flanges soon fractured and loosened the edge units. If an 30 asphalt pavement be spread closely against the rails the flanges of the wheels so severely punished the borders as to very soon distort and fracture them. The automobile, especially trucks, contributed to the progressive 35 injury of the borders of the pavement strips under consideration.

The object of my invention is to provide a remedy for the previous faulty, unsightly ultimately expensive and sometimes dangerous 40 constructions.

I propose the use of curbing as elongated units, with appropriate modification opposite the fish plates employed at the rail joints, which it is my initial intention to 45 factory form of rich concrete and preferably embracing metal reenforcement. The curb-

ing includes an upper pavement surface substantially level with the rail treads while another upper surface portion nearest the rail is depressed and projects below the rail 50 head to form in conjunction with the side of the rail head a trough of adequate depth and width for any expectable movement of the wheel flange. Preferably, the curbing is slightly spaced from the rail to permit of 55 the positioning therebetween of a suitable yielding substance to allow for rail vibration. Pitch may be poured in said longitudinally extending space. After the rails are adjusted and fixed in place and a suitable 60 sub-foundation has been provided, I support the curbing in its proper spaced relation to the rail. This may be accomplished by temporarily clamping the curbing sections to the rails or in any other satisfactory manner 65 holding them in place during the time required for an indurating foundation to become hard. Thereafter, any preferred type 70 of pavement may be laid between the two runs of curbing so as to be flush with the 75 pavement surfaces of the latter.

Adverting to the drawings:

Fig. I is a perspective view of one of the 80 novel elements, the curbing, of my railway construction.

Fig. II is a vertical cross-section of a railway track together with its sub-foundation and also showing on one side one of my curbing elements temporarily clamped in 85 place.

Fig. III is a view corresponding to Fig. II with the addition as a further step in the method of a layer of concrete in which the curbing elements, inwardly adjacent both 90 rails, are shown to be partially embedded.

Fig. IV is a sectional view similar to Figs. II and III after completion of the method, the temporary clamps having been removed and the upper surfacing pavement layer added. Broken views of a pair of car wheels 100 are also illustrated.

Fig. V is an enlarged broken view of a part of Fig. IV.

Fig. VI is a perspective view of a precast concrete curbing modified by the provision 105 of a lateral recess for occupation by a fish plate.

My curbing element 1, preferably precast of rich concrete is reinforced by a tie rod arrangement 2. The lower side of the 110 curbing is roughened at 3 as by serrations or corrugations. The upper side of the

curbing for about one-half of its width is depressed at 4 to a depth substantially equal to the thickness of the head of a rail for a purpose hereinafter to appear. The larger upright wall 5 of the curbing element will be observed to extend at a slight angle from the vertical with respect to the bottom 3 and so that the latter slopes upwardly in a direction toward the opposite side of the curbing element. The curbing element 1 may be of any desired length, breadth and thickness as may be determined by the conditions with which the contractor is confronted.

Upon the sub-foundation 6 rails 7 have their bases 8 rest. The rails 7 are provided with heads 9 of conventional shape. Railway ties (not shown, since common to the art) may be employed to hold the rails in proper alinement. The curbing elements 1 are then caused to rest upon a suitable number of supports 10 so that the thinner sides of the curbing elements project underneath the head 9 of the rail. Any suitable type of clamp 11 co-acts to hold the curbing elements temporarily in a position in which they appear in Figs. II and III. It will be observed that a slight space is left between the smaller sides of the curbing element and the rail. The purpose of providing this free space will be later explained. Next, concrete 12 is poured in between the rails, appropriately tamped underneath the curbing elements which are inwardly adjacent a pair of parallel rails, and allowed to indurate to approximately the level shown in Fig. III, after which the clamps 11 may be removed. As will be observed in Fig. III opposed sides 5 converge in a downward direction. Thereafter, pitch 13 or any other suitable yielding substance is poured into the open space provided between the smaller side of the curbing elements and the inside of the rail as is clearly shown in Fig. V. The object of the pitch 13 is to permit of rail vibration without causing displacement of the curbing elements as will be readily understood by those skilled in the art. Finally, the upper layer of pavement 14, asphalt being shown, is spread upon the concrete 12 and rolled to have a slightly convex upper surface, the sides of which being level with the tops of the curbing elements. When completed the depressions 4 will provide clearing space for flanges 15 of car wheels 16, and the clearance will be sufficient both downwardly and sideways to allow any expectable play of the wheel flange as suggested by the dotted lines at the left side of Fig. IV.

My railway pavement construction will be seen to provide a uniformly adequate channel adjacent the inner side of the rail head for all except inordinate wheel movements. Even if the wheel flange should oc-

casionally strike one of my curbing elements, the length and strength of the latter will be able to resist the punishment to which it might be subjected. The whole construction will tend to maintain its shape, 70 while loads carried by the surface 14 will tend to spread the curbing elements outwardly and to hold them in proper position with respect to the rails.

The modified form shown in Fig. VI illustrates the curbing element 17 provided with a lateral cut-out 18 as the space to be occupied by a fish plate and will evidence applicant's recognition that other suitable modifications should be made to some of 80 the curbing elements to adapt them to frogs, switches, etc.

I claim:—

1. The method of making a railway construction which consists in temporarily supporting elongated rail curbing so as to extend lengthwise alongside of the inner sides of a pair of parallel rails forming a track, and so as to be spaced therefrom, and then supplying an induratable mass of material 90 underneath said curbing.

2. The method of making a street railway which consists in supporting elongated rail curbing elements in an elevated position and so that their longitudinal dimensions are substantially parallel to and spaced from a pair of parallel rails respectively, pouring pitch in between said adjacent rails and curbing elements and then laying a pavement underneath and between 100 said curbing elements.

3. The method of making a pavement between the rails of a street railway which consists in temporarily supporting curbing on said rails in desired position inwardly 105 adjacent to each rail, supplying an indurated foundation for said curbing, and thereafter laying a pavement between said runs of curbing.

4. In a railway pavement construction 110 intended for between the rails, the combination of two elongated curbing elements extending lengthwise, one inwardly adjacent each rail, each of said elements being fashioned with an inclined and roughened surface, and indurated material between said elements and conforming to said inclined and roughened surfaces.

5. In a railway pavement construction 115 intended to be located between a pair of rails, the combination of two concrete curbing elements each inwardly adjacent and spaced from one rail and provided with roughened bottom surfaces, and an indurated support contacting said bottom surfaces.

6. The combination with a pair of track-forming rails, of two curbing elements wider than said rails and extending lengthwise along the inner sides of the latter re- 120 125 130

spectively, said curbing elements each having a depressed upper surface adjacent a rail head to form in conjunction therewith a trough of adequate depth and width for any expectable movement of a car wheel flange and said curbing elements furthermore having their sides which are opposed to each other diverging in an upward direction and a pavement foundation laid both underneath and between said curbing elements.

7. The combination with a pair of parallelly spaced rails of two elongated curbing elements extending lengthwise alongside of said rails respectively, said curbing elements having their sides which are opposed to each other diverging in an upward direction, a yielding substance between said rails and curbing elements and pavement laid between said curbing elements and abutting the opposed sloping sides thereof whereby loads sustained by said pavement tend to move said curbing elements apart.

8. The method of making a pavement between the rails of a street railway which consists in temporarily supporting, inwardly adjacent each rail, curbing elements the bottom surfaces of which are fashioned with cavities and so that said bottom surfaces are elevated and then packing an induratable material underneath said curbing elements.

9. The method of making a pavement between the rails of a street railway which consists in temporarily supporting, inwardly adjacent though spaced from each rail, curbing elements the bottom surfaces of which are fashioned with longitudinally extending serrations and so that said bottom surfaces are elevated, supplying a yielding substance between said rails and elements and then packing a permanent induratable foundation material underneath said curbing elements.

Signed by me, this 7 day of July, 1924.

MATTHEW F. BRAMLEY.
